CLAIM

The ornamental design for a display screen with a graphical user interface, as shown and described.

DESCRIPTION

FIG. 1 is a first image in a sequence for a display screen with a graphical user interface showing the new design;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is an eighth image thereof;

FIG. 9 is a ninth image thereof;

FIG. 10 is a tenth image thereof;

FIG. 11 is an eleventh image thereof; and,

FIG. 12 is a twelfth image thereof.

The subject matter in this patent includes a process or period in which an image changes into another image. This process or period forms no part of the claimed design.

The outer broken lines showing a display screen and the remaining broken lines showing portions of the graphical user interface form no part of the claimed design.
